OTHER PUBLICATIONS

U.S. Appl. No. 29/390,448, Applicant: Lee, et al., filed Apr. 25, 2011 entitled Netbook Computer.

(Continued)

Primary Examiner — Freda S Nunn

(74) Attorney, Agent, or Firm — Wood, Herron & Evans, LLP

(57) **CLAIM**

The ornamental design for netbook computer, as shown and described.

DESCRIPTION

FIG. 1 is a top front perspective view of a netbook computer showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.
